[57] CLAIM

The ornamental design for a chocolate maker, as shown and described.

DESCRIPTION

FIG. 1 is a top elevation view of a chocolate maker showing my new design;

FIG. 2 is a left side elevation view thereof;

FIG. 3 is a bottom plan view thereof;

FIG. 4 is a right side elevation view thereof;

FIG. 5 is a rear elevation view thereof;

FIG. 6 is a front elevation view thereof; and,

FIG. 7 is an exploded perspective view of the invention.

The surfaces or portions of the article not shown in the drawing or described in the specification form no part of the claimed design.
